C. C. Freeman
ATTORNEY

UNITED STATES PATENT OFFICE

HENRY B. ROTBERG, OF NEW YORK, N. Y.

CLASP

Application filed December 20, 1928. Serial No. 327,203.

This invention relates to devices for connecting objects or parts thereof in adjusted relation.

One object of the invention is to provide a flexible bar having frictional engaging clamps at each end adapted to readily slip onto any thin object to be held in adjustment with respect to another, without damage to the articles and which may be readily re-
10 moved when desired.

A further feature is in the provision of spring band reinforcements whereby the jaws of the clamps are pressed firmly towards each other to afford an efficient grip.

15 Another purpose is to produce a double ended clip, with or without length adjustment, that can be applied or removed instantly, no pins, buttons, or analogous securing means being employed.

20 These and other advantageous objects, such as lightness of weight, pleasing appearance and economy of manufacture, are attained by the novel construction and combination of parts hereinafter described and shown in
25 the accompanying drawing, forming a material part of this disclosure, and in which:

Fig. 1, is a perspective view showing one application of the clip.

Fig. 2, is a detail perspective view of the
30 clip drawn to an enlarged scale.

Fig. 3, is a partial plan view of a modified form of the invention.

The device, which is essentially simple in character, consists of a bar 5, preferably a thin strip of flexible sheet material, as celluloid, of parallel thickness and width.

40 The ends of this bar, which may be of any length compatible with its purpose, are bent to produce looped rings 6 their reentrantly turned extremities 7 being slightly outturned as shown, to readily engage any thin object, as the folds of the dress as illustrated in Fig. 1.

45 Although the inherent resilience of the material may be sufficient to cause the jaw element 7 to tightly press against the bar, at the initial bend of the ring, a firm and secure grip is secured by embracing the loop or ring 6 with a reinforcing ring 8, which

may be partially embedded therein or otherwise secured in any preferred manner.

In the modified form of clip, shown in Fig. 3, a pair of bars 5' are formed with loops 6' at one end only, the looped ends 55 terminating in jaw elements 7' and the loops are provided with spring reinforcements 8' in the manner previously described.

The opposite ends of the bars are preferably bent slightly outward to form stops 9 60 adapted to limit the movement of the bars within a clasp 10 by which the bars are held in operative relation.

Although the foregoing is descriptive of the best known embodiment of the invention, 65 it is apparent that minor modifications may be resorted to and that the clip is not limited to sizes and proportions as may be made as desired, within the scope of the appended claims.

Having thus described the invention and set forth the manner of its construction and use, what is claimed as new and sought to secure by Letters Patent, is:—

1. A clip comprising a bar of flexible non-metallic material having an open loop at each end, jaws extending from said loops to seat upon the bar adjacent the loops, said jaws having outwardly curved terminals, and metal spring bands encircling said loops to 75 close the jaws upon the bar.

2. A clip comprising a pair of flexible non-metallic bars having loops at one end and re-entrant jaws disposed against the bars, said means consisting of spring metal bands en- 85 circling said loops, means to press the jaws against the bars, a clasp confining said bars, and stops on the opposite ends of the bars.

Signed at New York, in the county and State of New York, this 13th day of November, 1928.

HENRY B. ROTBERG.
